UNITED STATES PATENT OFFICE.

GILBERT WRIGHT, OF SCHENECTADY, NEW YORK, ASSIGNOR TO GENERAL ELECTRIC COMPANY, A CORPORATION OF NEW YORK.

ELECTRIC-LIGHTING APPARATUS.

1,271,980.

Specification of Letters Patent.

Patented July 9, 1918.

Application filed March 11, 1914. Serial No. 823,954.

To all whom it may concern:

Be it known that I, GILBERT WRIGHT, a citizen of the United States, residing at Schenectady, county of Schenectady, State of New York, have invented certain new and useful Improvements in Electric-Lighting Apparatus, of which the following is a specification.

My invention relates to electric lighting apparatus and electric circuit connections, and especially to sockets or receptacles for electric lamps and the like and to the mounting of such lamps and sockets in reflectors and in lanterns. It is my aim to make the lamp conveniently accessible when mounted in a lantern; to enable it to be easily and quickly focused or adjusted with reference to its reflector so as to give whatever intensity and distribution of light may at the moment be desired; to permit the lamp and its reflector to be readily removed from the lantern and used as a portable light or searchlight; and to combine serviceability, durability, and a good appearance with simplicity and ruggedness of construction and ease and cheapness of manufacture. These and various other advantages that will hereinafter become apparent especially adapt the invention to the lighting equipment of automobiles; but its utility is not by any means restricted to this field.

My invention comprises various novel features of construction and various novel parts and combinations and arrangements of parts that will be hereinafter set forth by the illustration and description of the best forms of apparatus embodying them at present known to me, and will be definitely pointed out and distinguished in my claims,— for while my invention extends to various specific features and details shown and described, it is not confined thereto. Moreover, while I have shown and described my invention as embodied in simple form of apparatus constructed on the single wire system commonly employed for automobiles, it will be understood that many, at least, of its features are applicable in other systems of wiring.

In the accompanying drawing, Figure 1 is a sectional view through a lantern suitable for use as an automobile headlight, certain of the internal parts being also partially broken away or in section.

Fig. 2 is an enlarged sectional detail view

of the parts directly involved in the mounting of the lamp.

Fig. 3 is a separate view (not in section) of one of the parts shown in Fig. 2 turned 90° from the position shown in that figure. 60

Fig. 4 is a view similar to Fig. 1 of certain of the inner parts of the lantern, showing a modified form of construction.

Fig. 5 is an enlarged fragmentary detail view illustrating the construction shown in Fig. 4, certain parts being removed or partially broken away. 65

Fig. 6 is a view similar to Fig. 4 with various parts in section.

Figs. 7 and 8 are enlarged detail views of certain parts shown in Figs. 1, 2 and 3, Fig. 7 being an end view, and Fig. 8 a longitudinal section. 70

Figs. 9 and 10 are views similar to Figs. 7 and 8 showing a modified form of construction, the parts being shown as turned 90° from the position in those figures. 75

Figs. 11, 12 and 13 are longitudinal sectional views illustrating a coupling or connecting plug device suitable for flexible cord circuits,—as, for example, the exterior supply connection of the lantern shown in Fig. 1. 80

The automobile headlight lantern shown in Fig. 1 comprises an ordinary metal casing 1, a glazed front 2 hinged thereto in the usual way, and a parabolic metal reflector structure 3 for the incandescent electric lamp 4 secured to the inside of the front 2 by means of a flange 5 that fits in the frame 6 behind the glass. It will be seen, therefore, that the reflector structure 3 can readily be applied to old oil, acetylene, or electric headlight lamps, as well as to new lamps especially designed for it. The reflector structure 3 comprises an annular flaring front part or section 7 whose outer front edge carries the flange 5,—and which, as shown, forms part of the reflector surface,—and a concave rear part or section 8 at whose center the lamp 4 is mounted. The front section 7 has at its inner rear edge a flange 9 so shaped as to form a good seat for the rear section 8,—the front edge of such rear section being turned back in a bead 10 adapted to fit snugly in said seat. The rear section 8 is detachably secured in place against the front section 7 by means of hooks 11 having a T shape and attached to helical springs 12 (or, as shown in Fig. 4, 100

105

110

consisting merely of the bent ends of the spring 12) that are in turn secured to lugs 13 riveted to the flange 5, the points of the hooks 11 lying in notches in the flange 1 and 5 engaging in the groove at the rear of the bead 10. By merely opening the door 2 and releasing the hooks 11, the rear reflector section 8 can be removed and the lamp 4 itself made conveniently accessible, as well as 10 its current supply means and connections. As shown, the current supply means comprise a liberal length of flexible wire cord 14, so that the lamp 4 with the reflector section 8 may conveniently be removed from 15 the lantern and used anywhere about the automobile as a powerful "trouble" lamp, or as a searchlight, etc.,—the cord 14 being easily coiled away in the casing 1 when the lamp 4 is to be restored to its normal position in the lantern.

The means employed for the mounting of the lamp 4 in the reflector 3 and for the relative adjustment of the lamp and the reflector comprise a part associated with the former 25 and provided with engaging means, such as notches, at different positions lengthwise thereof and a part associated with the latter and having corresponding engagement means, such as one or more pins or studs, or 30 vice-versa,—said parts being capable of relative rotary as well as longitudinal movement to bring the pins or the like into and out of engagement in the various notches. As shown in Fig. 1, the part associated with 35 the reflector 3 is a hollow cylindrical sleeve or socket part or shell 15 on which a split collar 16 brazed in the reflector section 8 is secured by a screw clamp ring 17; the corresponding part associated with the lamp 4 is 40 its cylindrical base 18, of the bayonet type; and the engagement means belonging to these two parts comprise a plurality of notches 19 at the front edges of the inclined portions 20 of openings 21 in the shell 15 45 that resemble bayonet slots and the ordinary bayonet pins 22 of the base 18. The base 18 has end contact means 23 for engaging with the socket contact means 24 to which the conductor of the flexible cord 14 is connected, the return circuit being through the bayonet pins 22 and the shell 15. The contact means 24 is movably and insulatively mounted in the socket structure and is yieldingly urged forward or outward into engagement with the lamp base 18 by a helical spring 25. This spring 25 thus tends to 50 shift the parts 15 and 18 lengthwise with reference to one another in the direction to cause engagement of the pins 21 in the notches 19, besides acting to hold the lamp base 18 securely in contact with the contact means 24 when the pins are engaged in any of said notches. The location and number of the notches 19 will correspond to the 55 variations of illumination and delicacy of

adjustment desired; as shown, there are two notches 19 for each slot 21, corresponding to the focal or parallel beam and moderately extensive positions of the lamp 4 in the reflector 3. To make an ordinary service adjustment, it is only necessary to detach the rear reflector section 8 and turn the lamp 4 in the socket. Extraordinary adjustments (to take care of differences in the location of the filament in the lamp 4, for example) 70 may be made by means of the screw clamp ring or strap 17.

Referring now to Fig. 2 as well as Fig. 1, it will be seen that the socket contact means 24 consists of the forwardly projecting portion of a member 26 mounted in a hollow part 27 of insulating material, and that, in addition to the notches 19 already mentioned, each bayonet slot 21 has a notch 28 opening from in front of the inclined portion 20. It will further be seen that there is a sleeve-like member 29 of insulating material around the forwardly projecting portion 24 of the contact member 26, and that there is a helical spring 30 arranged in a recess at the rear of the insulating member 29 and tending to push it forward on the portion 24 of the contact member beyond the end thereof and so separate the latter and the lamp base 18. The dimensions and scales of the springs 25 and 30 are so chosen that when the pins 21 are in any of the notches 19 the force of the former will exceed that of the latter and the contact means 24 will engage the lamp base 18, but that when the base 18 is turned and the pins 21 are shifted into the notches 28 the spring 30 will prevail so as to push the member 29 beyond the end of the contact means 24, so that the latter and the lamp base 18 will be 95 pushed apart—coacting shoulders 31 and 32 on the parts 15 and 29, respectively preventing any of the parts from being forced too far outward—and securely held out of contact with one another. This method of 100 lighting and extinguishing the lamp 4 by shifting it in its socket is advantageously applicable to automobile tail-lamps for use in places where the law requires that it be impossible to extinguish them from within 105 the machine, as well as to headlight and other lamps.

It will be observed that the action of the various operating parts by which the lamp 4 is lighted and extinguished as just described 110 results from the variation in the length of the space for them behind the lamp base 18 produced by the longitudinal shifting of the lamp 4 in the socket, and that the same action would result from a similar variation produced without any disturbance of the lamp. In the structure shown, means for extension and contraction of the space behind the lamp base 18 additional to the notches 19 and 28 are accordingly provided 115 120 125 130

by making the rear portion 33 of the shell or casing structure that incloses the operating parts separate from the front portion 15 which receives the lamp base 18 and is secured in the reflector 3 and adjustable with reference thereto. From Figs. 2 and 3 it will be seen that the enlarged rear end of the part 15 has engagement means comprising inwardly projecting studs or bayonet pins 34, and that the part 33 fits within it and has corresponding engagement means in the form of notches 35 and 36 in the opposite edges of the slot-like openings 37. The notches 35 and 36 associated with each slot 37 are so located that by turning the part 33 and shifting the corresponding pin 34 from the former to the latter or vice-versa the lamp 4 will be extinguished or lighted by the same action of the interior parts as when it is itself shifted in its socket. While just as applicable to tail-lamps, etc., as that first described, this latter mode of producing the necessary action of the parts is more convenient for lanterns such as shown in Fig. 1, for example, because it does not necessitate detachment of the rear reflector section 8.

In Figs. 4, 5 and 6 I have shown a modified construction that permits the adjustment of the lamp 4 with reference to the reflector 3 to be effected without detachment of the rear reflector section 8, omitting the turning on and off feature for the sake of simplicity of construction and illustration. As here shown, the hollow cylindrical socket part or shell 40 that receives the lamp base 41 has an inclined opening or slot 42 entirely distinct from its bayonet slot 43 that receives the bayonet pin 44 of said base 41, and the notches 45 corresponding to the adjusting notches 19 of Figs. 1 and 2 are at the inclined front edge of this opening. The cylindrical collar or sleeve part 46 associated with the reflector 3 is itself adapted to slide and turn on the shell 40, and the engagement means corresponding to the bayonet pins 22 of Figs. 1 and 2 is a stud or pin formed by the inwardly projecting end (not visible) of a part 47 screwed through the wall of this sleeve. The means (corresponding to the spring 25) whereby this stud is caused to engage in the notches 45 and held so engaged consists of a helical spring 48 arranged between the reflector 3 and a flange 49 at the rear end of the shell part 40. The contact member 26 and the insulating part 27 that carries it are yieldingly urged outward and forward in the socket by the spring 25: these parts are in form and action like those of the same numbers in Figs. 1 and 2, although differently arranged. As shown, there are seven notches 45 so located as to give a range and delicacy of adjustment sufficient to take care of considerable irregularities in the location of the

incandescent body or filament 50 in the lamp 4 as well as to give all the variation of the light distribution likely to be desired. The adjustment is effected by merely taking hold of the milled or knurled edge of the flange 49 or of the lamp bulb 4 and manipulating the part 40 thereby so as to shift the stud or pin 47 from one notch 45 to another; and this does not affect the current supply circuit of the lamp 4, the desired adjustment can be made very quickly and certainly.

Referring, now, more particularly to the contact member 26 and the insulating means 27 that form the contact device employed in the structures of Figs. 2 and 6, and first to the former, it will be seen from these figures and from Figs. 7 and 8 that said member 26 comprises cylindrical portions 56 and 24 of different diameters, that there is a slot 57 extending lengthwise through the larger portion 56 into the smaller portion 24 nearly to its end, and that there is a common bore 58 extending clear through both portions. It will further be seen that oppositely facing screws 59 in the portion 56 at opposite sides of the bore 58 afford means for clamping the parts into which the member is divided by the slot 57 together on a conductor, said parts undergoing flexure in the smaller portion 24 to permit this. As for the insulating part 27, it will be seen that it is a sleeve of insulating material (such as vulcanite or fiber) which is reduced at one end so as to fit within the spring 25 and has its own bore 60 enlarged at the other end at 61 to take the large portion 56 of the member 26 with a snug or even rather tight fit. The rest of the bore 60 is of such a size as to be adapted to receive the smaller portion 24 of the member 26 rather loosely.

When the smaller portion 24 of the contact member 26 is to project and make contact, as in Fig. 2, the cord 14, for example, is passed through the part 27 from its reduced end, its conductor is stripped of insulation for a suitable distance and inserted and clamped in the bore 58 at the large end of the member 26, and said member 26 is inserted and pushed home in the enlarged bore of the part 27 at 61, as shown in Fig. 2. When the larger portion 56 is to be exposed and make contact, the flexible cord 14 is passed through the part 27 in the same way; but the stripped conductor is inserted in the bore 58 at the small end 24 of the member 26 and after it is clamped the small end 24 is inserted and pushed home in the bore at 61 as shown in Fig. 6.

In Figs. 9 and 10 I have shown a modified form of contact member 126 differing from that just described in having its slot 157 wider in the portion 156 and in having but a single screw 159 for clamping together the parts into which it is divided. This arrangement allows the conductor to be bent around

the screw 159 before the parts are clamped together upon it.

In Figs. 11 and 12 I have shown a coupling or connecting plug device suitable for flexible cord circuits (such as that of the lamp shown in Fig. 1, for example) constructed in accordance with my invention. The part 70 shown in Figs. 1 and 11 is substantially like the socket of Fig. 6, except that its shell 71 is a little longer and lacks the opening 42 and the flange 49. The part 72 shown in Fig. 12 has a shell or casing 73 very much like the part 15 of Fig. 2, but closed at its right-hand end by an ornamental closure like that shown in Figs. 2, 6 and 11. In this shell 73 are parts 26 and 27 arranged as in Fig. 2, but no spring. When the parts 70 and 72 are put together with the bayonet pins of the shell 73 in the simple bayonet slots of the shell 71, the spring 25 of the part 70 keeps the contact members 26 of the two parts engaged. It will be observed that the contact members 26 in both parts are protected by the ends of their shells when the parts are separated.

In Fig. 13 I have shown a plug part 75 adapted to be used with the part 70, but differing from the part 72 of Fig. 12 in being quite short, in having its shell 76 fit inside the shell of the part 70, in having external bayonet pins or studs 77, and in having its parts 26 and 27 put together like those of the part 70. This plug part 75 makes the connecting device as a whole quite short.

What I claim as new and desire to secure by Letters Patent of the United States, is:—

1. In a mounting device for an electric lamp, the combination of parts associated, respectively, with the lamp and with the structure carrying it and fitting one within the other, one of said parts having notches at different positions lengthwise thereof and the other having means adapted to engage in said notches, said parts being capable of relative movement to bring such means into and out of engagement in the various notches and alter the position of the lamp with reference to the aforesaid structure, and spring means tending to shift said parts lengthwise with reference to one another and thereby bring about engagement of said means in said notches.

2. In a mounting device for an electric lamp, the combination of a hollow part for receiving the lamp base associated with the structure carrying the lamp, a contact member adapted to engage with the end of the lamp base in said hollow part, and means tending to push the lamp base outward in said hollow part, said hollow part having notches for receiving a pin on the lamp base at different positions lengthwise thereof, so that the position of the lamp with reference to the aforesaid structure may be adjusted

by manipulating the lamp so as to engage the pin in the various notches.

3. In a mounting device for an incandescent electric lamp, the combination of a contact device comprising insulating means and a contact member projecting therefrom, an insulating member fitting about the projecting portion of said contact member, spring means around said projecting portion acting to force said insulating member toward the projecting end thereof, a casing associated with the structure carrying the lamp inclosing the parts aforesaid and having a socket for the base of the lamp, and spring means in the casing urging said contact device toward the open end of the socket, said socket having a plurality of notches for a bayonet pin on the lamp base at different positions lengthwise of the socket such that when the pin is in one of them the lamp base will be held out of contact with said contact member by said insulating part and that when said pin is in the others the lamp base will be in contact with said contact member with its filament in different positions with reference to the aforesaid structure.

4. In a mounting device for an electric lamp, the combination of parts associated, respectively, with the lamp and with the structure carrying it and fitting one within the other, one of said parts having notches at different positions lengthwise thereof and the other having means adapted to engage in said notches, said parts being capable of relative rotary and longitudinal movement to bring such means into and out of engagement in the various notches and alter the position of the lamp with reference to the aforesaid structure, and spring means tending to shift the parts lengthwise with reference to one another in the direction to cause engagement of said means in said notches.

5. In a mounting device for an electric lamp, the combination of a sleeve part associated with the structure carrying the lamp, a cylindrical part in said sleeve part associated with the lamp, one of said parts having a slot with an inclined edge having notches therein and the other part having means adapted to engage in said notches, said parts being capable of relative rotary and longitudinal movement to bring such means into engagement in the various notches and alter the position of the lamp with reference to the aforesaid structure, and spring means tending to shift the parts lengthwise with reference to one another in the direction to cause engagement of said means in said notches.

6. The combination of a casing comprising separate parts, one of which has a socket for a lamp base, said parts being longitudinally adjustable with reference to one an-

- other so as to extend or contract the space in the casing behind a lamp base in the socket, contact means in the casing for engaging the lamp base, and spring means in the casing which acts to separate the lamp base and the contact means when the space is extended and permits them to come together when it is contracted.
7. A socket comprising a casing structure having a socket adapted to receive a lamp base, said casing structure including means whereby the space behind a lamp base in the socket may be longitudinally extended or contracted, a contact member in said casing structure for engaging the end of the lamp base, an insulating member in said casing structure around the contact member, and a spring acting to urge said insulating member outward in the casing beyond the end of said contact member so that when the space is contracted the lamp base will be in contact with said contact means and that when the space is extended the lamp base and said contact member will be pushed apart.
8. A contact device comprising a sleeve of insulating material having a portion of reduced diameter at one end and having a large bore at one end and a small bore at the other, a hollow contact member having a portion fitting in the larger bore of said
- 5 the casing which acts to separate the lamp base and the contact means when the space is extended and permits them to come together when it is contracted.
9. A contact member having portions of different diameter and a slot extending lengthwise through the larger portion and into the smaller portion, so that the parts into which said member is divided may be made to approach one another by flexure in the smaller portion, and screw threaded means associated with the larger portion for clamping the parts thereof together upon a conductor between them.
10. A hollow contact member having cylindrical portions of different diameters and a slot extending lengthwise through the larger portion and into the smaller portion, so that the parts into which said member is divided may be made to approach one another by flexure in the smaller portion, and screws in the larger portion at opposite sides of its bore for clamping the parts together upon a conductor in said bore.

In witness whereof, I have hereunto set my hand this 10th day of March, 1914.

GILBERT WRIGHT.
